UNITED STATES PATENT OFFICE

167,593

CHAIR

Harry B. Shephard, San Francisco, Calif., assignor to Akwei Corporation, a corporation of California

Application September 4, 1951, Serial No. 16,497

Term of patent 14 years

(Cl. D15—11)

To all whom it may concern:

Be it known that I, Harry B. Shephard, a citizen of the United States, residing in the city and county of San Francisco, State of California, have invented a new, original, and ornamental Design for a Chair, of which the following is a specification, reference being had to the accompanying drawings, forming a part thereof:

Fig. 1 is a perspective view of the chair in open position, and showing my new design.

Fig. 2 is a perspective view of the chair in collapsed position.

I claim:

The ornamental design for a chair, as shown.

HARRY B. SHEPHARD.
